(57) CLAIM

The ornamental design for table lighter, substantially as shown and described.

DESCRIPTION

FIG. 1 is a front, right and top side perspective view of table lighter, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a partial enlarged view of FIG. 1;

FIG. 9 is a partial enlarged view of FIG. 2; and,

FIG. 10 is a partial enlarged view of FIG. 6.

The broken lines consisting of evenly spaced dash lines in the drawing depict portions of the table lighter that form no part of the claimed design. The broken lines encircling the enlarged detail views are for annotative purpose that form no part of the claimed design.
